**PROCESS FOR MANUFACTURING OLEFINS
AND DIOLEFINS**

Henry R. Linden, Franklin Park, Jack M. Reid, Villa Park, and Wilford G. Bair, Chicago, Ill., assignors to Institute of Gas Technology, Chicago, Ill., a corporation of Illinois

Application March 22, 1956, Serial No. 573,124

7 Claims. (Cl. 260—683)

This invention relates to an improved process for making ethylene and other olefinic hydrocarbons by thermally cracking petroleum oils and similar liquid or liquefiable fossil fuels. A primary object of the invention is to provide a process of this kind characterized by greatly increased yields of olefins from a wide range of starting materials or feed stocks.

Another object is to provide a process for thermally cracking the feed stock in the presence of hydrogen, wherein the hydrogen is derived from the cracking process itself in the form of a hydrogen-rich tail gas, which remains after removal of the desired olefins and diolefins from the make gas.

The invention consists of dispersing the feed stock in hydrogen, or a hydrogen-rich carrier gas, which has been preheated to cracking temperature, and subsequently cracking the dispersed feed stock under carefully controlled conditions. For optimum yields of all olefinic and diolefinc products, total pressures must not exceed 20 p.s.i.g., and low partial pressures attained by high steam dilutions are favorable. The severity of cracking may be adjusted, by variation of the average cracking temperature and feed rates, to give optimum yields of the desired olefins. At feed rates resulting in residence times from 1 to 5 seconds, propylene, butylene and butadiene production will be favored at temperatures below 1400° F., and optimum total olefin yields will be obtained at 1400–1600° F. At 1600–1800° F. and over one second residence time, olefin yields will consist primarily of ethylene. When using the low-cost, high molecular weight, high carbon-to-hydrogen ratio feed stocks such as residual petroleum or shale oils and coal or lignite tar residues, the process is carried out preferably in a cyclic regenerative cracking apparatus wherein a major portion of the feed stock is introduced countercurrent to the flow of preheated hydrogen-rich carrier gas. Cyclic operation provides a simple and economic method of handling carbon deposited in all cracking operations. The increased yields in olefins and diolefins resulting from our process are remarkable and not at all expected, since one would predict that the presence of hydrogen would reduce the yield of unsaturated compounds. However, it was found that the total conversion of liquid fossil fuels such as petroleum oils, to gaseous hydrocarbons and especially olefins and diolefins, was much greater when the feed was contacted with highly preheated hydrogen-rich carrier

2

gas, than when the feed and the hydrogen gas were brought to cracking temperature together. For example, cracking of a low cost petroleum oil (residual oil) at 1400° F. and 3–5 seconds residence time in a cyclic regenerative apparatus after dispersing the oil in hydrogen-rich carrier gas (equivalent to 45–50 standard cubic feet of pure hydrogen per gallon of oil) flowing countercurrent to the oil, resulted in increases in ethylene production of over 50% and more than doubled the production of propylene, butenes and butadiene, as compared with the same process practiced without use of preheated hydrogen-rich gas. The net production of gaseous constituents was increased by approximately 50% and the production of tar and coke correspondingly reduced.

With distillate oil, an approximate 50% increase in ethylene production was obtained, using hydrogen-rich carrier gas preheated to 1650° F., at 1600–1700° F., 2–4 seconds and the equivalent of 45–50 standard cubic feet of pure hydrogen per gallon of oil. When these feed stocks and hydrogen were introduced into a tube furnace without preheating of the hydrogen, no significant change in olefin and diolefin yields was observed under similar operating conditions.

The feed stocks suitable for use in the process of the invention may be described broadly as "liquid or liquefiable fossil fuels" which term, when used in this specification and in the appended claims, is intended to include propane, butane, liquefied petroleum gases (LPG), petroleum oils (distillate and residual), shale oils and liquid products obtained in the carbonization of solid fuels. Except for some constituents in shale oils and carbonization products, these materials all fall largely within the chemical class of hydrocarbons. One of the important advantages of the present process is that it utilizes a wide variety of feed stocks including those which are very low in cost. The feed stock is preferably preheated and then introduced in the form of droplets, a finely-divided mist, or in vapor form, into a stream of hydrogen or hydrogen-rich carrier gas which has been preheated to a temperature of from 1200 to 1800° F.

The hydrogen content of the hydrogen-rich gas (referred to herein as "pure" hydrogen) should be in excess of 50%. The ratio of pure hydrogen in the carrier gas to feed stock will range up to 100 standard cubic feet per gallon. It will be understood, of course, that the optimum ratio of hydrogen to feed stock will vary in accordance with the carbon-to-hydrogen ratio of the feed stock. Generally, the amount of hydrogen required for optimum olefin production increases proportionally to the

carbon-to-hydrogen ratio of the feed stock up to a maximum of 100 standard cubic feet per gallon. Beyond this point hydrogenation of the olefins and diolefins will occur under the prevailing cracking conditions. We have found that for petroleum feed stocks from 30 to 60 standard cubic feet of hydrogen per gallon is a practical range when residual product gas is the source of hydrogen.

Preferably, the feed stock is sprayed countercurrent to the flow of the heated hydrogen-rich stream into a suitable cracking vessel maintained at a temperature of

from 1300 to 1800° F. (such as a generator of a cyclic oil gas set) to produce a uniform dispersion of liquid droplets or vapor throughout the gas. The gas stream carrying the liquid droplets of feed stock or containing vaporized feed stock is then cracked at a pressure ranging from subatmospheric up to 20 p.s.i.g. at a residence time which must not exceed 10 seconds and preferably should be less than 5 seconds. The cracking vessel or vessels contain no catalyst, the cracking being carried out entirely by heat. Carrier steam in substantially quantities may be used in addition to the hydrogen-rich gas to control residence time, to sweep the reaction products from the cracking vessel, and to reduce the partial pressure of the reacting hydrocarbons. The quantity of steam may range up to ten times the volume of hydrogen confined in the hydrogen-rich gas. The upper limit will vary with the capacity of the apparatus for transferring heat to the reactants and its permeability to gas flow.

Upon cracking of the feed stock in the presence of hydrogen, product gas is formed which contains from 25-45% hydrogen, 25-35% methane, 2-8% ethane, 15-25% ethylene, 2-10% propylene, 1-5% butenes and butadiene, and smaller concentrations of other gaseous hydrocarbons. Benzene and toluene concentrations depend on the efficiency of the liquid condensing system, while dilution with products of combustion (nitrogen and carbon dioxide) depends on the operation of the cracking apparatus. Normally, the stable product gas will have a heating value of 900-1200 B.t.u. per standard cubic foot and a specific gravity of 0.5 to 0.75 on an inert-free basis.

In a preferred form of the invention, after the olefins and diolefins are removed from the make gas, the tail gas remaining is recycled into the system as the hydrogen-rich carrier gas. Thus, it is possible, in accordance with the present process, to generate within the process itself sufficient hydrogen-rich gas to serve as the carrier and hydrogen atmosphere during cracking of the feed stock. High methane and ethane concentrations of the hydrogen-rich carrier gas are not unfavorable to the process, but any significant amount of olefins and diolefins must be avoided to prevent suppression of olefin and diolefin formation during cracking of the feedstock. We prefer to use a hydrogen-rich gas containing not more than about 1% olefins and diolefins (see runs 11, 18 and 19 in table below).

A suitable apparatus for practicing the process of the invention is illustrated in the single figure of the drawing, which shows diagrammatically a four-shell cyclic regenerative apparatus, and the flow of materials through the apparatus. The unit consists of four interconnected shells 21, 11, 12 and 22. The vessels 11 and 12 are the No. 1 and No. 2 generators. They are interconnected by a crossover 14 near the upper ends thereof and contain a few courses of checkerbrick 16 near the lower end thereof. Vessels 21 and 22 are the No. 1 and No. 2 regenerators. These vessels connect to the lower end of the adjacent generator through identical conduits 18 and 20. The vessels are refractory lined to resist elevated temperatures. The regenerators 21 and 22 are filled with refractory shapes 25 which are capable of absorbing and releasing heat to fluids passing therethrough. A pair of tar receivers 24 and 26 connect to conduits 18 and 20, one for each generator-regenerator pair. They are joined to the conduits by means of T's 27, 29. Heat oil burners and make oil nozzles (not shown) are located in the top of each generator for purposes of spraying these materials into the generators. Make steam and purge steam connections from common supply line 53 connect to the top of each of the regenerators through vertical pipes 54, 56.

Air for the purpose of burning carbon and tar which is laid down in the generators during cracking, and for combustion of heat oil, is supplied from blower 46 through conduit 48. Branch lines 50 and 52 connect line 48 through suitable valves to the pipes 54 and 56. Ex-

haust stacks 55 and 57 connect to the tops of regenerators 21 and 22. The make gas leaves the set through conduits 30 and 32 connecting to the side of tarpots 24 and 26, respectively. Suitable pressure regulator 34 is inserted in the line 32 for purposes of regulating the pressure within the generators and regenerators. First and second stage condensers 36 and 38 are provided for condensing steam and light oils in the make gas. The product gas is discharged from the lower end of second stage condenser 10 38 through line 40 and meter 42. To provide cool tar for quenching make gas in the tarpots, a circulating system is employed which permits tar to flow from the tarpots through lines 31, 33 and 35 to the tar cooler 44 and back to the pots through line 37. The tar is collected through vertical drain lines 39 and 41. Water for quenching the product gas issuing from the conduit 18 is provided through lines 43 and 45 which connect just below the T's 27, 29 connecting the tarpots to conduits 18 and 20.

The gas-fired heater 58 is provided for preheating the make oil, or other liquid feed stock, prior to introduction into the set through line 60. The system, of course, is equipped with suitable valves and controls which permit flexibility for changing the cycle length as desired. Details with respect to the construction of this four-shell set 20 and other cyclic sets suitable for use in practicing the present invention are shown and described in an application of Elmore S. Pettyjohn and Henry R. Linden, Serial No. 424,012, filed April 19, 1954.

In cracking fossil fuels in accordance with this invention, using the apparatus illustrated in the drawing, the first step is a forward make cycle during which hydrogen-rich carrier gas and make steam, if desired, enter the top of the regenerator 21 through which they flow downwardly to absorb heat from the regenerator which has previously been heated. The preheated hydrogen and steam then flow to the generator through conduit 18 and upwardly through generator 11. Make oil or other liquid feed stock, which preferably has been preheated in preheater 58, flows from the line 60 and downwardly through the branch line 63 which has a suitable spray head (not shown) connected to the end thereof inside the generator 11. Thus, the feed stock is sprayed in very fine droplet form downwardly as the preheated hydrogen-rich gas or mixture of hydrogen and steam flows upwardly. Cracking is initiated in generator 11 and the products pass over through crossover 14 into generator 12 where cracking is completed. Additional make oil may be introduced at the top of the generator 12 if the desired cracking reactions can be completed before the entire reaction mass leaves generator 12 through conduit 20. The cracking time and the partial pressure of the reactive constituents (hydrocarbons and hydrogen) may be conveniently controlled by adjusting the volume of steam which serves to sweep the reactants and product gases through the set. 30 The products of cracking are withdrawn through the T 29 in the tarpot 26 where they are quenched with cooled recycle tar sprays to reduce the temperature to approximately 300-600° F. Condensed tar, which is deposited in the bottom of the pot, is continuously circulated through the cooler 44 and back up to the top of the pot through line 37 for this purpose. A suitable method and apparatus for cooling gases with tar and for recovering tar in dry form is shown and described in Patent No. 2,719,819 to Elmore S. Pettyjohn. Quench water from line 45 may be used to supplement the tar if the temperature is not reduced sufficiently. From the tarpot the make gas passes through the back pressure regulating valve 34 into the condensing system. At the conclusion of the make period, which may range from less than one to over five minutes, the bypass valve 66 is opened, bleeding the pressure within the set down to essentially atmospheric.

The make period is followed by a steam purge wherein steam from the supply source 53 enters the top of the regenerator 21 through the pipe 54 following the same path as the make products just described. The valve

in the stack 57 is opened and the blast is started in the same direction as the make. This period is initiated by bringing air into the top of the regenerator 21 through the line 50. The introduction of air into the set causes carbon and tar which have been laid down in the generator 11 during the make period to burn, thus releasing large quantities of heat for bringing the generator up to the desired temperature. The products of combustion flow downwardly through generator 12 through connector conduit 20, and upwardly through regenerator 22 giving up their heat to the checkerbrick therein, and are discharged from the stack 57. Depending upon the particular type of feed stock employed, the carbon lay-down may be large or it may be almost negligible. In using the light hydrocarbons as feed stock, the carbon lay-down will be held to a minimum, and in such case it is necessary to inject considerable heat oil into the generator 12 in order to bring the generator and the checkerbrick in regenerator 22 up to the desired temperature for heating the incoming hydrogen-rich gas. At the conclusion of the blast period, which may require from less than one to over five minutes, the stacks are reversed and the blast gas is purged from the set in the reverse direction with the purge steam entering the regenerator 22 and being discharged through the stack 55 after traversing the entire set. The make period in the opposite direction is then initiated. Hydrogen or hydrogen-rich gas is introduced from lines 61, 56 into the top of regenerator 22 where it picks up heat and flows through the conduit 20 upwardly through the generator 12. Simultaneously liquid fuel or make oil is introduced in the form of a spray at the top of the generator 12 countercurrent to the flow of the hydrogen or hydrogen-rich gas. Cracking is initiated in the No. 2 generator 12 and the cracking products together with uncracked make oil, which is thoroughly dispersed in the hydrogen-rich gas, passes through the crossover 14 into the generator 11 where the cracking reaction is completed. Additional make oil can also be introduced in generator 11. The make gas flows through conduit 18, T 27, tarpot 24, line 30 and into the condensing system. The process is then repeated in the reverse direction, as previously described.

It will be noted that in accordance with this process none of the make products pass through the regenerators. The make gas passes from the bottom of the generators into the tarpot and is discharged therefrom through either line 30 or line 32 into the condensers. Consequently, all deposited coke and pitch is confined to the generators. The absence of fouling makes it possible to obtain extremely high efficiencies in regenerator operation and avoid smoke at the start of the blast without the use of the air purge.

A typical 8 minute operating cycle giving the valve sequence for gasification of either No. 2 furnace oil or reduced crude oil in the apparatus shown in the drawing is given below:

TYPICAL CYCLE OF VALVE SEQUENCE

Valve function:	Seconds
No. 1 make oil open	0
No. 1 hydrogen open	2
No. 1 hydrogen close	82
No. 1 make oil close	83
Bypass open	83
No. 1 purge steam open	110
No. 1 make steam close	118
No. 2 stack open	120
Bypass close	123
No. 1 purge steam close	125
No. 1 air blast open	125
No. 2 heat oil open	129

Valve function:	Seconds
No. 2 heat oil close	214
No. 1 air blast close	217
No. 2 stack close	217
No. 1 stack open	217
No. 2 purge steam open	217
No. 1 stack close	233
No. 2 purge steam close	241
No. 2 make steam open	241
No. 2 make oil open	241
No. 2 hydrogen open	243
No. 2 hydrogen close	323
No. 2 make oil close	324
Bypass open	324
No. 2 purge steam open	351
No. 2 make steam close	357
No. 1 stack open	361
Bypass close	364
No. 2 purge steam close	365
No. 2 air blast open	365
No. 1 heat oil open	368
No. 1 heat oil close	454
No. 2 air blast close	457
No. 1 stack close	457
No. 2 stack open	457
No. 1 purge steam open	457
No. 2 stack close	473
No. 1 purge steam close	482
No. 1 make steam open	482
No. 1 make oil open	482

This cycle may be varied in overall length from less than 6 minutes to over 20 minutes; the relative length of the individual valve functions, and the valve function sequence may also be changed within the limitations set by the process specifications. For example: Make oil may be introduced into both generators during the make period; the blast following the make period may proceed in the opposite direction from the preceding make; the set may be filled or pressurized with steam and/or hydrogen before the make; and stack valve reversal and steam purge techniques may be varied to be convenient for the apparatus or exact operating cycle employed. Conventional fluid bed or moving bed operation, in which the heat requirements are supplied by a stream of a suitable heat transfer medium which is reheated in a separate vessel or zone, may be substituted for cyclic operation. Continuous or semi-continuous operation in tube furnaces or other externally heated reactors, can also be used, especially with the lower molecular weight, lower carbon-hydrogen weight ratio feed stocks, as long as the hydrogen-rich carrier gas is preheated to 1200-1800° F. before contacting the feed stock, intimate mixing of feed stock and preheated hydrogen is effected, and the reaction mass is maintained at 1300-1800° F. for not over 10 seconds at pressures not exceeding 20 pounds per square inch gauge.

Utilizing the cycle set forth above, test runs were made in the apparatus described using distillate oil and reduced crude oil as the feed stocks. A direct comparison was made between the cracking process utilizing preheated hydrogen carrier gas and cracking without any hydrogen whatsoever. The reduced crude oil was characterized by 23° API, 7.0% carbon-to-hydrogen ratio, and 5.3% by weight Conradson carbon residue. The distillate oil had the following specifications: 34° API, 6.6% carbon-to-hydrogen ratio, and 0% by weight Conradson carbon residue. Run 7 on the distillate oil and runs 16 and 17 on the reduced crude oil were without hydrogen. Run 11 for distillate oil and runs 18 and 19 for the reduced crude oil were with hydrogen. The table set forth below gives the complete operating conditions and results for cracking of these oils, including a detailed analysis of the make gas, flue gas and the process hydrogen (hydrogen-rich gas) which served as the carrier gas.

Operating result from cyclic four-shell high-B.t.u. oil gas pilot plant on 34° API, 6.6 C/H ratio, 0 wt. percent Conradson carbon residue distillate oil and 23° API, 7.0 C/H ratio, 5.3 wt. percent Conradson carbon residue due reduced crude oil

¹ By difference.² Calculated from flue gas analyses and assumed to contain 6% hydrogen.

In comparing runs 7 and 11 it will be noted that the ethylene yield was increased from 13.87% to 20.03% of make oil. Similar improvements were shown for reduced crude, the yield being increased from 18.50% to 27.90% (runs 16 and 19) and from 16.35% to 25.75% (runs 17 and 18). The increase in propylene was particularly great in cracking of reduced crude oil as a comparison of runs 16 and 17 with companion runs 18 and 19 will indicate. The difference between runs 17 and 18 is almost tenfold. Greatly increased yields of butenes and of butadienes were also obtained.

The heating values set forth in the table above indicate that the gas produced in accordance with the present process is suitable as a high B.t.u. fuel gas.

It will be understood that the foregoing examples are merely illustrative of the invention and that similar results may be obtained utilizing different feed stocks, apparatus and other operating conditions within the limits set forth in this specification.

What we claim as new and desire to secure by Letters Patent of the United States is:

1. A process for making a gas rich in olefins and diolefins from a feedstock taken from the group consisting of liquefied petroleum gases and liquid fossil fuels, which comprises introducing a stream of hydrogen-rich gas containing at least 50 volume percent hydrogen and not more than about 1% olefins and diolefins, preheated to 1200° to 1800° F., into a cracking vessel maintained at cracking temperature and at a pressure ranging from subatmospheric to 20 pounds per square inch gauge, dispersing said feedstock in finely divided form in said hot, gaseous stream at a rate of one gallon per 30 to 100 standard cubic feet of pure hydrogen to crack the feedstock as it flows through the cracking vessel to form a gaseous product containing olefins and diolefins, the residence time in said cracking vessel not exceeding 10 seconds, and separating said olefins and diolefins from said gaseous product.

2. The process of claim 1 wherein said hydrogen-rich gas consists of pure hydrogen.

3. A process for making a gas rich in olefins and diolefins from a feed stock taken from the group consisting of liquefied petroleum gases and liquid fossil fuels, which comprises introducing a stream of hydrogen-rich gas containing at least 50 volume percent hydrogen, preheated to 1200° to 1800° F., into a cracking vessel maintained at cracking temperature and at a pressure ranging from subatmospheric to 20 pounds per square inch gauge, dispersing said feedstock in finely divided form in said hot, gaseous stream at a rate of one gallon per 30 to 100 standard cubic feet of pure hydrogen to crack the feedstock as it flows through the cracking vessel to form a gaseous product containing olefins and diolefins, methane, ethane and hydrogen, the residence time in said cracking vessel not exceeding 10 seconds, separating said olefins and diolefins from said gaseous product and recycling said residual gas containing at least 50% hydrogen, methane and ethane as said hydrogen-rich gas.

4. A process for making a gas rich in olefins and diolefins from a feedstock taken from the group consisting of liquefied petroleum gases and liquid fossil fuels, which comprises introducing a mixture of hydrogen-rich carrier gas containing at least 50 volume percent hydrogen and not more than about 1% olefins and diolefins, and diluent steam preheated to 1200° to 1800° F., into

a cracking vessel maintained at 1300° to 1800° F. and at a pressure ranging from subatmospheric to 20 pounds per square inch gauge, dispersing said feedstock in finely divided form in said mixture of hydrogen-rich carrier gas and steam at a rate of one gallon per 30 to 100 standard cubic feet of pure hydrogen to crack the feedstock as it flows through the cracking vessel at residence times of 1 to 10 seconds into a product gas containing olefins and diolefins, and separating said olefins and diolefins from said gaseous product.

75 5. A process for making a high B.t.u. fuel gas from

a feedstock taken from the group consisting of liquefied petroleum gases and liquid fossil fuels, which comprises introducing a stream of hydrogen-rich gas containing at least 50 volume percent hydrogen and not more than about 1% of olefins and diolefins, preheated to 1200° to 1800° F., into a cracking vessel maintained at cracking temperature and at a pressure ranging from subatmospheric to 20 pounds per square inch gauge, dispersing said feedstock in finely divided form in said gaseous stream at a rate of one gallon per 30 to 100 standard cubic feet of pure hydrogen to crack the feedstock as it flows through the cracking vessel to form said high B.t.u. fuel gas.

6. A process for making a gas rich in olefins and diolefins from a petroleum oil which comprises introducing a stream of hydrogen-rich gas containing at least 50 volume percent hydrogen and not more than about 1% olefins and diolefins preheated to 1200° to 1800° F. into a cracking vessel maintained at a temperature of 1300° to 1800° F. and at a pressure ranging from subatmospheric to 20 pounds per square inch gauge, spraying said oil into said hot gas stream at a ratio of 30 to 100 standard cubic feet of pure hydrogen per gallon of oil to crack the oil as it flows through the cracking vessel to form a gaseous product containing olefins and diolefins having from 2 to 4 carbon atoms, the residence time in said cracking vessel not exceeding 10 seconds, and separating said olefins and diolefins from said gaseous product.

7. A process for making a gas rich in olefins and diolefins from a feedstock taken from the group consisting of liquefied petroleum gases and liquid fossil fuels, which comprises dispersing said feedstock in a hydrogen-rich carrier gas stream having a temperature of 1200° to 1800° F. at a rate of 1 gallon of feedstock per 30 to 100 standard cubic feet of pure hydrogen, said hydrogen-rich gas containing at least 50 volume percent hydrogen, introducing said stream into a cracking vessel maintained at a temperature of 1300° to 1800° F. and pre-pressurized with steam to a pressure not in excess of 20 pounds per square inch gauge, to crack said feedstock as it flows through the cracking vessel to form a gaseous product containing olefins, diolefins, hydrogen, paraffinic hydrocarbons, light aromatics and tar vapors, the residence time in said cracking vessel not exceeding 10 seconds, quenching said gaseous product to condense out said light aromatics, steam and tar vapors, separating the olefins and diolefins from the quenched product gases and recycling the gas containing hydrogen and paraffinic hydrocarbons for use as said hydrogen-rich carrier gas.
